UNITED STATES PATENT OFFICE

162,789

PAPER MATCH BOOK PACKAGE

John F. Carse, Omaha, Nebr.

Application June 26, 1950, Serial No. 10,762

Term of patent 14 years

(Cl. D48—28)

To all whom it may concern:

Be it known that I, John F. Carse, a citizen of the United States, residing at Omaha, in the county of Douglas and State of Nebraska, have invented a new, original, and ornamental Design for Paper Match Book Package, of which the following is a specification, reference being had to the accompanying drawing, forming part thereof.

Figure 1 is a front view of a paper match book package, showing my new design.

Figure 2 is a rear view thereof.

Figure 3 is an end view thereof.

I claim:

The ornamental design for a paper match book package, as shown.

JOHN F. CARSE.
